UNITED STATES PATENT OFFICE.

ROBERT G. LE TOURNEAU, OF STOCKTON, CALIFORNIA.

SCRAPER.

Application filed January 12, 1924. Serial No. 685,751.

To all whom it may concern:

Be it known that I, ROBERT G. LE TOURNEAU, a citizen of the United States, residing at Stockton, county of San Joaquin, State of California, have invented certain new and useful Improvements in Scrapers; and I do declare the following to be a full, clear, and exact description of the same, reference being had to the accompanying drawings and to the characters of reference marked thereon, which form a part of this application.

This invention relates to improvements in dirt scraping and transporting devices, the principal object of my invention being to provide a device of this character provided with a plurality of telescoping earth-supporting surfaces, arranged to be moved so that the uppermost and foremost surface, when loaded, may be moved back with its load, exposing the next surface for loading, and so on until the entire structure if desired is loaded.

This construction enables a very large amount of dirt being scraped and carried with but a relatively small expenditure of power, since the main factor which limits the size of the ordinary single-scoop scraper for practical purposes is the great resistance offered to the loading of the dirt when the latter has to pile up on itself and move back by the pressure of the incoming dirt against that already loaded. Much less power is required to move the entire dirt-loaded surface back, since relatively frictionless bearings may be provided for the said surface, and the only resistance offered to such movement is the weight of the mass of dirt.

Another object of my invention is to provide for the discharge of the dirt at the desired point without having to raise the dirt-bearing surfaces, and in such a manner that the discharge of the load is under the perfect control of the operator, so that but little or all of the dirt may be deposited in one heap, or it may be distributed over a considerable area and at widely spaced points if desired.

A further and important object is to provide a self-propelled scraper, in which a highly desirable flexibility of control and speed of the various working or driven

members is had by providing electric power means for controlling the steering and forward movement of the machine as a whole, and the movements of the dirt-carrying surfaces mounted thereon.

These objects I accomplish by means of such structure and relative arrangement of parts as will fully appear by a perusal of the following specification and claims:

In the drawings similar characters of reference indicate corresponding parts in the several views:

Fig. 1 is a side elevation of the complete apparatus.

Fig. 2 is a longitudinal section of the scraping structure proper, showing the dirt-carrying surfaces fully extended.

Fig. 3 is a similar view, showing the position of dirt-carrying surfaces prior to the final expanding movement, or after the first contracting movement has taken place.

Fig. 4 is a fragmentary side view of the scraper structure, with the dirt-carrying area fully contracted.

Fig. 5 is a similar view, showing the position of the dirt-carrying surfaces after the first expanding movement has taken place, or prior to the final contracting movement.

Fig. 6 is a sectional view of the dirt carrying surfaces when the latter are fully telescoped.

Fig. 7 is a front view of the scraper structure, the front supporting carriage being removed.

Fig. 8 is a somewhat enlarged typical cross section of the scraper, foreshortened, showing a pair of telescoped load-carrying members.

Fig. 9 is a fragmentary detail showing a catch structure mounted in connection with those supporting surfaces shown superimposed in Fig. 3, the catch being disengaged.

Fig. 10 is a similar view of the same structure, showing the catch as engaged when the next supporting surface is moved forward to lie on those already superimposed.

Referring now to the characters of reference on the drawings, 1 denotes the forward framework of the structure, supported by a pair of wheels 2; and 3 is the rear main

framework of the scraping and load-carrying structure, supported adjacent its rear end by a pair of wheels 4.

The frame 1 is swivelly connected to the frame 3 by means of a centrally located vertical and fixed sleeve 5 of considerable length, in which is slidably and turnably mounted a shaft 6. A rigid strut 7 extends from the top of this shaft to a hinged connection 7^a with the frame 1, while the lower end of said shaft is also rigidly connected to the frame 1 with a similar hinged connection 7^b. These hinges are arranged to allow lateral swivelling of the frames 1 and 3 relative to each other, as when uneven ground is encountered.

The sleeve and shaft are moved vertically at will, or held in fixed positions relative to each other by means of a cable 8, the ends 20 of which are wound on separate drums 9 mounted on the framework 3, passing thence up about pulleys 10 at the top of the shaft 6, then down about pulleys 11 connected to the sleeve 5 or frame 3, and thence upward and about a pulley 12 mounted in connection with the shaft 6 between the pulleys 10. The drums 9 are driven from a reversible electric motor 13 mounted on the framework 3, a suitable speed-reduction 30 mechanism being interposed between the drums and motor.

About the portion of the shaft 6 projecting below the sleeve 5 is fixed a collapsible sleeve 14, to protect the shaft from the adjacent dirt without interfering with its vertical movement.

Mounted on the frame 1 is a gas engine unit the front end of which is conventionally illustrated at 15 in Fig. 1. This engine 40 drives a dynamo 16, of sufficient capacity to provide current for running the motor 13, as well as the others hereinafter mentioned.

The engine and dynamo are so located on the frame 1, relative to the axis of the wheels 2 and the pivotal connection of the frame 3 therewith, as to counterbalance the weight supported by its rear end, thereby reducing the bending strains on the shaft 6.

The wheels 2 each has an electric motor 50 17 to drive the same, so that steering of the machine may be aided in the well known manner of stopping or reversing one wheel while allowing the other one to turn.

The rear wheels 4 are also preferably 55 driven in the same manner by electric motor means 18.

Steering of the structure apart from any steering had by manipulation of the driving wheels, is provided for by arranging a cable 19 wrapped about a drum 20 mounted on the frame 3 adjacent the wheels thereof, said cable extending thence along the outside of the frame 3 to connections with the opposite sides of the frame 1 near its rear 65 end. It will therefore be seen that with this

arrangement, rotation of the drum will cause the cable to slack up on one side and pull on the other, causing a turning movement of the frame 1 to take place about its pivotal axis 6. The drum 20 is also driven 70 by a reversible electric motor 21 mounted on the frame 3. (See Fig. 2.)

Mounted in the frame 3 between the front end thereof and the wheels 4 is the scraping and dirt carrying structure. This comprises a horizontal load carrying structure A of certain length, rigidly fixed in the frame 3, and which is made up of a horizontal surface 22 having a scraping blade 23 extending transversely at its forward end, and side walls 24. This structure is the first to be discharged and the last to be loaded.

Slidably mounted in the frame 3 are additional load-carrying members, preferably 85 four in number, and designated as B, C, D, & E. These each comprise floor members 25 and side walls 26, said members B to E being arranged to telescope into each other in the sequence named, so that their floors lie 90 in superimposed order on the surface 22 as shown in Fig. 6, or to be extended or drawn away from the latter so as to form a continuous surface, with their forward ends overlapping the rear ends of adjacent floors, 95 as shown for instance in Fig. 2.

The floor of the member E curves upwardly toward its rear end on a radius, the center of which forms the pivotal connection for an end gate 27 turnable between 100 stops 28 fixed on the side walls of said member E.

At the rear ends of, and under, the members B to E are transverse stiffening beams 29, which also serve as stops to limit the 105 telescoping movement of said members on each other.

These beams, at their transverse ends, carry rollers 30 (see Fig. 8) which ride on track means 31 provided on the frame 3, 110 thereby lessening the friction of horizontal movement of the dirt supporting members.

Between adjacent beams 29 are mounted chains 32 or other flexible members, for the purpose of limiting the extending movement 115 of the supporting surfaces relative to each other.

Horizontal movement is imparted to the members B, C, D, & E, to cause them to telescope or to be extended, by means of 120 cables 33 wound about drums 34 mounted on the frame 3, behind the plane of the load structure E when fully extended. The rear ends of these cables are attached to the rear face of the end gate 27, while the forward ends are attached to the forward face of said end gate, extending thence forwardly to the forward and fixed structure A, and thence over suitably located pulley means 35 to the drums. Shock-absorbing 125

springs 36 are preferably interposed in the cables at suitable points.

The drums 34 are driven through the medium of a reversible electric motor 37, 5 mounted on the frame 3.

Individual controllers for the different motors are mounted at a suitable location on top of the framework 3, as shown at 38, there being a seat 39 for an operator arranged adjacent thereto. The various necessary leads between the dynamo, motors, and the control members, being flexible, it is an easy matter to run them wherever there is available space for the same. These 10 different leads, which any ordinary electrician may readily connect up, have not been shown, as the necessary arrangement thereof forms no part of my invention.

It will therefore be seen that the entire 20 operation of the machine, including loading, dumping, travelling and steering, may be all attended to by a single operator, with but negligible physical effort on his part being necessary, and being positioned on top 25 of the machine, he has a commanding view of the entire situation.

In order to insure that the telescoping structures will move evenly, and without any tendency to bind laterally, I provide 30 over each such a structure a rigid transverse shaft 40, to the ends of which are fixed rigid arms 41 which extend to pivotal connections with the rear ends of the sides of adjacent and forwardly lying structure. 35 In other words, the arm 41 from the shaft 40 above the structure E is connected to the rear end of the structure D; that from the shaft above the structure D is connected to the structure C, and so on. Turnable 40 on the shafts 40 are rigid sleeves 42, to the ends of which are fixed arms 43, which extend to pivotal connections with the rear ends of the sides of the telescopic structures above which the corresponding sleeves 45 are located.

In other words, the arms 43 from the sleeve 42 above the structure E is connected to the rear end of the latter; those from the sleeve above the structure D are connected to the latter adjacent the connection of the arms 41 therewith, and so on.

With this arrangement therefore, the distance which the structure E moves in or out of the structure D for instance, must 55 be the same on both sides, since the contraction or spread of the arms 41 and 43 on one side, and which are connected to both structures D and E, must be the same as the contraction or spread of the corresponding arms on the other side, since each pair of arms, with its connecting member, forms a rigid unit.

I have also provided automatically acting catch means for preventing undesired 60 extending movement of the load-carrying

structures when telescoped, without depending on the pull on the cables 33 to hold them in such position. These catches are at present only applied to hold the unit B from moving away from the fixed unit A, 70 and also to independently hold the unit D from moving away from the unit A.

The first named catch device comprises a horizontal and notched latch bar 44 pivoted on each side member of the unit A and facing toward the unit B. On each of the arms 43 attached to the latter is a lug or pin 45 adapted to align with the notch of the latch bar only when said arm 43 and the cooperating arm 41 are in their contracted positions, which is when the structures A and B are fully telescoped into each other.

On each of the adjacent arms connected to the structure B is a trip arm 46, arranged to engage and raise the bar 44 clear of the pin 45 as long as said arm 41 is in its expanded or substantially horizontal position, which is when the structure C is drawn out of the structure B. When however the 90 arms 41 and 43 of the structure C are contracted or drawn together with the telescoping of the structure C into the structure B, the trip arm is lowered clear of the latch bar 44, allowing the latter to drop 95 onto and engage the pin 45, and the latter will not then be released until the structure C is again moved out of and away from the structure B. This catch structure is particularly illustrated in Figs. 9 and 10. 100

The other catch structure, particularly illustrated in Figs. 4, and 5, is substantially the same in general construction and operation as that just described.

It comprises a horizontal and notched 105 catch bar 47 pivoted on each side of the dirt carrying structure on an extension 3^a of the frame 3, or on any other fixed member found suitable.

This latch bar faces toward the rear, and 110 its notch is arranged to receive a lug or pin 48 fixed on the side member of the unit D when the latter is telescoped into the unit C. Until the unit E is telescoped into the unit D however the latch bar 47 is held from engagement with the pin 48 by a trip arm 49 fixed on and projecting from that arm 41 which is attached to the unit D.

In other words, as long as said arm and the cooperating arm 43 are expanded, as 120 when the unit E is drawn out of the unit D, the bar 47 will not engage the pin 48, but as soon as said arms have moved together a certain distance with the telescoping of the unit E into the unit D, the arm 48 moves clear of the bar 47, allowing the latter to engage the pin 48.

The operation of the machine is as follows:

Assuming to start that the scraper is 130

empty, the dirt-carrying units are fully telescoped, and it is now desired to scape, transport and dump a load.

The machine having been moved to the place where the scraping is to be done, the blade or scraping edge 23 is lowered to engage the ground by moving the sleeve 5 down on the post 6.

Forward movement of the machine will then cause dirt to be moved into the uppermost supporting surface, which is that of the unit E.

The gate 27 having been first swung back to about against the rear stop 28, the floor surface of said unit E is clear for the reception of the dirt. When this surface has been loaded, the operator will cause a rearward pull to be exerted on the lower runs of the cables 33, drawing the unit E rearwardly, and exposing the floor surface of the adjacent unit D for loading. This withdrawal of the unit E is preferably not carried out to its full extent at one time, but gradually and as the unit D is loaded. This insures that the pile of dirt will be in the form of a solid and level mass, rather than as a series of peaked or ridged piles, as would otherwise be the case.

When the unit E has been withdrawn until the connecting chains 32 are taut, the catches 47, up to this time holding the unit D against movement, are automatically released in the manner previously described.

This allows the unit D to be moved rearwardly to clear the unit C, and so on until all the units form a continuous and level floor, loaded from one end to the other. The blade 23 is then raised from the ground by pulling up on the sleeve 5, and the machine may then be transported to the place where the load is to be dumped.

To dump the load, the manipulation of the dirt carrying units is the reverse of that had with the loading operation.

A forward pulling strain is imparted to the lower runs of the cables 33, tending to cause the end gate 27 to move forwardly from the rear to the front stop means 28.

Such movement will not likely be had at this time however, since the entire mass of dirt from end to end of the structure, is resisting the same. Any movement will take place where there is the least resistance, which will be between the units B and A, since to move the former onto the latter, only the relatively small load in the unit A has to be shifted forwardly and dumped.

Each unit will thus be telescoped in order, from the fixed unit A back to the unit E. When the latter has moved onto the unit D, the end gate will then move forwardly, clearing said unit E of dirt, since the previous resistance to such movement has been removed.

When this last movement has taken place, 65 the scraper is empty, and loading operations may then be again carried out, after moving the end gate to its rearward position, as previously stated.

From the foregoing description it will be 70 readily seen that I have produced such a device as substantially fulfills the objects of the invention as set forth herein.

While this specification sets forth in detail the present and preferred construction 75 of the device, still in practice such deviations from such detail may be resorted to as do not form a departure from the spirit of the invention as set forth herein.

Having thus described my invention what 80 I claim as new and useful and desire to secure by Letters Patent is:

1. A scraper including a frame, and a plurality of dirt-supporting units mounted therein for horizontal telescoping and extending movement.

2. A scraper including a frame, a plurality of dirt-supporting units mounted therein for horizontal telescoping and extending movement, and means for imparting 90 such movement in either direction at will.

3. A scraper including a frame, a plurality of dirt-supporting units mounted therein for horizontal telescoping and extending movement, and an endgate mounted in the 95 rearmost unit and movable to clear the floor of the same of any load of dirt thereon.

4. A scraper including a frame, a plurality of dirt-supporting units mounted therein for horizontal telescoping and extending 100 movement, and means for limiting the telescopic or extended movement of the units relative to each other.

5. A scraper including a frame, a plurality of dirt-supporting units mounted therein for horizontal telescoping and extending 105 movement, means for imparting such movement, and means causing the units to be positively held in transverse alinement with each other, thereby preventing any binding 110 therebetween.

6. A scraper including a frame, a plurality of dirt-supporting units mounted therein for horizontal telescoping and extending movement, means for imparting 115 such movement, rigid transverse shafts over the individual units, arms fixed thereon and pivotally secured to the rear ends of adjacent units, sleeves turnable on said shafts, and arms fixed on said sleeves and pivotally 120 secured to the rear ends of the units under the corresponding sleeves.

7. A scraper including a frame, a plurality of dirt-supporting units mounted therein for horizontal telescoping and extending movement, catch means holding certain of the units immovable relative to the frame when said units are telescoped, and 125

means whereby said catches are automatically released as adjacent units are moved to their extended positions.

8. A scraper including a frame, a plurality of dirt-supporting units mounted therein for horizontal telescoping and extending movement, catch means holding certain of the units immovable relative to the frame when said units are telescoped, and 10 means mounted in connection with the units adjacent to those engaged by the catches for automatically releasing the latter as said adjacent units move to their extended positions.

15. 9. A scraper including a frame, a plurality of dirt-supporting units mounted therein for horizontal telescoping and extending movement, an endgate pivotally mounted in the rearmost unit and arranged 20 for limited movement, and horizontally extending pull cables attached to both faces of the gate.

10. A scraper including a frame, a plurality of dirt-supporting units mounted 25 therein for horizontal telescoping and extending movement, an endgate pivotally mounted in the rearmost unit and arranged for limited movement, horizontally extending pull cables attached to both faces of the 30 gate, and means mounted on the frame for pulling the cables in either direction.

11. A scraper including a frame, a plurality of dirt-supporting units mounted 35 therein for horizontal telescoping and extending movement, an endgate pivotally mounted in the rearmost unit and arranged for limited movement, and means for exerting horizontal and longitudinal pressure on the endgate in both directions.

40. 12. A scraper including a frame, a plurality of dirt-supporting units mounted therein for horizontal telescoping and extending movement, an endgate mounted in the rearmost unit, means for applying horizontal and longitudinal pressure to the endgate in both directions, and means whereby 45 such pressure will cause telescopic or extending movement to be imparted to the units.

50. 13. A scraper including a plurality of dirt-carrying units having horizontal floors, means whereby dirt may be loaded onto each unit in turn from the forward end of the scraper, and means whereby such dirt may 55 be discharged from said front end without tilting the floors upwardly.

14. A scraping structure comprising a scraping unit, a driving structure connected to said unit at one end thereof, a common means for permanently connecting said structure and unit to enable the adjacent end of the unit to be raised and lowered and to enable relative turning movement between said unit and structure being had, power means for controlling the raising and lowering movement, independent power means for controlling the turning movement, and individual control means mounted on the scraping unit for controlling the operation of both said first named means. 70

15. A scraping apparatus comprising a wheel-supported frame, a steerable wheel structure connected to the frame, a relatively movable scraping structure in the frame, independent power means for driving the 75 wheels, manipulating the scraping structure and controlling the steering of the steerable structure; and individual control means for all said power means mounted on the frame in centralized relation to each other. 80

16. A scraping apparatus comprising a wheel-supported frame, a steerable wheel structure connected to the frame, a relatively movable scraping structure in the frame, and independent power units for turning the 85 wheels, manipulating the scraping structure and controlling the steering of the steerable structure. 85

17. A scraping apparatus comprising a wheel-supported frame, a steerable wheel structure connected to the frame, a relatively movable scraping structure in the frame, independent power units for turning the 90 wheels, manipulating the scraping structure and controlling the steering of the steerable structure, and a common source of power for all said units carried by the apparatus. 95

18. A scraping apparatus comprising a wheel-supported frame, a steerable wheel structure connected to the frame, a relatively movable scraping structure in the frame, independent electric motors for turning the 100 wheels, manipulating the scraping structure and controlling the steering of the steerable structure, individual control means for said 105 motors at a centralized point on the apparatus; and a common source of current for all said motors carried by the apparatus.

In testimony whereof I affix my signature.

ROBERT G. LE TOURNEAU.
